A. E. BAUMANN

CONCRETE FORM

Filed Aug. 1, 1924

UNITED STATES PATENT OFFICE.

ALFRED E. BAUMANN, OF MILWAUKEE, WISCONSIN.

CONCRETE FORM.

Application filed August 1, 1924. Serial No. 729,521.

To all whom it may concern:

Be it known that I, ALFRED E. BAUMANN, a citizen of the United States, and resident of Milwaukee, in the county of Milwaukee, 5 and State of Wisconsin, have invented new and useful Improvements in Concrete Forms, of which the following is a description, reference being had to the accompanying drawings, which are a part of this specification.

The invention relates to forms for laying concrete, and more particularly for those used in building stairways.

The usual method of fabricating forms for 15 building concrete stairways consists of providing spaced inclined side form members joined by transversely extending riser form members held thereon by cleats, thin pieces of curved sheet metal being nailed to these 20 members at their abutment to form rounded corners at the ends of the risers. The preparation of the forms consumes a large portion of the time required to complete the stairway, and after the concrete has set it is 25 difficult to dismantle the forms without causing considerable damage to the concrete surfaces, which makes extensive patching necessary.

It is an object of the present invention to 30 provide corner form members for concrete stairways and the like which will facilitate the erection and dismantling of the other form members with which it cooperates, whereby economies will be effected in labor, 35 and damage to the concrete surfaces will be minimized.

The invention further consists in the several features hereinafter set forth and more particularly defined by claims at the conclusion hereof.

In the accompanying drawings: Fig. 1 is a fragmentary plan view of an assembled stairway form embodying the corner form member of the invention;

Fig. 2 is a longitudinal sectional view thereof, showing the concrete partially poured; and

Fig. 3 is a sectional view on a horizontal plane through the corner form member attached to its cooperating form members.

In these drawings, 10 indicates the usual inclined form members which are planks having their inner faces spaced from each other the width of the stairway, and 11 the 55 transversely extending riser form members.

The form members 10 and 11 are connected in their assembled relation by the corner or junction form members of this invention. Each of the corner form members comprises an angle bracket 12 of a height 60 for producing the riser desired and consists preferably of separate portions 13 and 14 secured together, 13 being the side portion and 14 the front portion, both being suitably flanged, if necessary for rigidity when 65 thin sheet metal is used.

The side portion 13 is adapted to abut against the inner face of the inclined form member, and is provided with slots 15 in its rear edge to receive fastening nails 16 driven 70 into the inclined form member, and slots 17 in its front edge to receive fastening screws 18, the front edge projecting beyond the front portion 14 of the bracket to afford facility in reaching the screws.

The front and side portions 13 and 14 of the bracket are joined by a fillet member 19 to form a curved end on the step, but may be omitted if square corners are desired.

In order to secure the transverse riser 80 form members to the brackets each of the brackets is provided with a plate 20 having aligned ears 21 pivotally mounted on the forwardly extending flanges 21 of the front portion of the bracket by rivets 22. The 85 riser form members are adapted to fit between the flanges 21 of each bracket, and the pivoted plate 20 is pressed into engagement with it by thumb screws 23 threaded on bolts 24 secured to the bracket and passing through slots 25 in the plate. The plate is also provided with stiffening flanges 26 which are preferably offset from the top and bottom edges so as not to interfere with troweling.

After the riser form members have been clamped at each end in the brackets and the brackets have been secured to the inclined side members, as hereinbefore described, to obtain the desired width of step, the completed forms are ready to receive the concrete aggregate, which is troweled in the usual manner. After the concrete has set the riser form members are readily removed from the brackets after loosening the thumb 100 nuts to permit the pivoted plates to be swung out. The screws 18 at the front of the corner brackets are then removed, which permits the brackets to be readily pulled forwardly along the side form members from 105 110

the attaching nails 16 disposed in the slots 15 in the rear edge of the brackets, after which the inclined side members can be lifted out of place. The removal of the form members is thus accomplished without disturbing the concrete, and obviates subsequent patching operations.

The outward pressure of the concrete on the riser form members is taken at the 19 screws 18, which are accordingly preferred to nails for this purpose, and the riser form members need not be cut accurately as to length provided sufficient clamping surface is present between the front portion 13 of 15 the corner bracket and the clamping plate 20.

The bracket of this invention is also useful in forming the corners of concrete slabs in general, as in side walks.

20 What I claim as new and desire to secure by Letters Patent is:

1. A corner form for concrete stairways comprising a concrete-retaining angle bracket having a portion for receiving the 25 end of a riser form member in laterally removable clamping engagement and another portion for attachment to the inner face of an inclined side form member and adapted for removal from and along said inclined 30 side member after the concrete has set.

2. A corner form for laid concrete comprising a concrete-retaining angle bracket, a clamping plate pivotally mounted thereon and cooperating with one portion thereof 35 for retaining the end of one form member between them in removable clamping engagement, and another portion for receiving a second form member at an angle to said first-named form member and adapted 40 for removal from and along said second member after the concrete has set.

3. A corner form for laid concrete comprising a concrete-retaining angle bracket having a portion for receiving one form 45 member in laterally removable clamping engagement and another portion for abutment against the inner face of a second form member at an angle to said first-named form member and having slots in 50 its end edge adapted to receive headed fastening members secured into said second

form member, whereby said bracket can be removed from and along said second form member after the concrete has set.

4. A corner form for laid concrete comprising a concrete-retaining bracket having a portion for receiving one form member in laterally removable clamping engagement and another portion for abutment against the inner face of a second form member at 60 an angle to said first-named form member and having slots in its rear edge and openings at its front edge adapted to receive headed fastening members secured to said second form member whereby said bracket 65 can be removed from and along said second form member after removing said last-named fastening members when the concrete has set.

5. A corner form for laid concrete comprising a concrete-retaining bracket having a flanged portion for receiving a form member against vertical movement, a clamping plate pivotally mounted on said bracket and cooperating with said flanged portion 75 for retaining said form member between them in removable clamping engagement, and another portion for receiving a second form member at an angle to said first-named form member and adapted for removal 80 from and along said second form member after the concrete has set.

6. A corner form for concrete stairways comprising a concrete-retaining bracket having a flanged portion for receiving a 85 riser form member against vertical movement, a clamping plate pivotally mounted on said bracket and cooperating with said flanged portion for retaining said riser form member in laterally removable clamping engagement, and another portion adapted 90 to abut against an inclined side form member, and having slots in its rear edge for receiving headed fastening members secured to said inclined member and openings 95 at its front edge for receiving removable headed fastening members, whereby said bracket can be removed from and along said inclined form member after the concrete has set.

In testimony whereof I affix my signature.

ALFRED E. BAUMANN.
